(57) **CLAIM**

I claim the ornamental design for a combined open sign with replaceable modules, as shown and described.

DESCRIPTION

FIG. 1 is a front perspective view of the sign portion of the combined open sign with replaceable modules, isolated for clarity of illustration;

FIG. 2 is a rear perspective of FIG. 1;

FIG. 3 is a front view of the FIG. 1;

FIG. 4 is a rear view of the FIG. 1;

FIG. 5 is a left view of the FIG. 1;
FIG. 6 is a right view of the FIG. 1;
FIG. 7 is a top view of the FIG. 1;
FIG. 8 is a bottom view of the FIG. 1;
FIG. 9 is a front perspective view of the first module;
isolated for clarity of illustration;
FIG. 10 is a rear perspective of FIG. 9;
FIG. 11 is a front view of the FIG. 9;
FIG. 12 is a rear view of the FIG. 9;
FIG. 13 is a left view of the FIG. 9;
FIG. 14 is a right view of the FIG. 9;
FIG. 15 is a top view of the FIG. 9;
FIG. 16 is a bottom view of the FIG. 9;
FIG. 17 is a front perspective view of the second module;
isolated for clarity of illustration;
FIG. 18 is a rear perspective of FIG. 17;
FIG. 19 is a front view of the FIG. 17;
FIG. 20 is a rear view of the FIG. 17;
FIG. 21 is a left view of the FIG. 17;
FIG. 22 is a right view of the FIG. 17;
FIG. 23 is a top view of the FIG. 17;
FIG. 24 is a bottom view of the FIG. 17;
FIG. 25 is a front perspective view of the third module;
isolated for clarity of illustration;
FIG. 26 is a rear perspective of FIG. 25;
FIG. 27 is a front view of the FIG. 25;
FIG. 28 is a rear view of the FIG. 25;
FIG. 29 is a left view of the FIG. 25;
FIG. 30 is a right view of the FIG. 25;
FIG. 31 is a top view of the FIG. 25;
FIG. 32 is a bottom view of the FIG. 25;
FIG. 33 is a front perspective view of the fourth module;
isolated for clarity of illustration;
FIG. 34 is a rear perspective of FIG. 33;
FIG. 35 is a front view of the FIG. 33;
FIG. 36 is a rear view of the FIG. 33;
FIG. 37 is a left view of the FIG. 33;
FIG. 38 is a right view of the FIG. 33;
FIG. 39 is a top view of the FIG. 33;
FIG. 40 is a bottom view of the FIG. 33;
FIG. 41 is a front perspective view of the fifth module;
isolated for clarity of illustration;
FIG. 42 is a rear perspective of FIG. 41;
FIG. 43 is a front view of the FIG. 41;
FIG. 44 is a rear view of the FIG. 41;
FIG. 45 is a left view of the FIG. 41;
FIG. 46 is a right view of the FIG. 41;
FIG. 47 is a top view of the FIG. 41;
FIG. 48 is a bottom view of the FIG. 41;
FIG. 49 is a front perspective view of the sixth module;
isolated for clarity of illustration;
FIG. 50 is a rear perspective of FIG. 49;
FIG. 51 is a front view of the FIG. 49;
FIG. 52 is a rear view of the FIG. 49;
FIG. 53 is a left view of the FIG. 49;
FIG. 54 is a right view of the FIG. 49;
FIG. 55 is a top view of the FIG. 49;
FIG. 56 is a bottom view of the FIG. 49;
FIG. 57 is a front perspective view of the seventh module;
isolated for clarity of illustration;
FIG. 58 is a rear perspective of FIG. 57;

FIG. 59 is a front view of the FIG. 57;
FIG. 60 is a rear view of the FIG. 57;
FIG. 61 is a left view of the FIG. 57;
FIG. 62 is a right view of the FIG. 57;
FIG. 63 is a top view of the FIG. 57;
FIG. 64 is a bottom view of the FIG. 57;
FIG. 65 is a front perspective view of the eighth module;
isolated for clarity of illustration;
FIG. 66 is a rear perspective of FIG. 65;
FIG. 67 is a front view of the FIG. 65;
FIG. 68 is a rear view of the FIG. 65;
FIG. 69 is a left view of the FIG. 65;
FIG. 70 is a right view of the FIG. 65;
FIG. 71 is a top view of the FIG. 65;
FIG. 72 is a bottom view of the FIG. 65;
FIG. 73 is a front perspective view of the ninth module;
isolated for clarity of illustration;
FIG. 74 is a rear perspective of FIG. 73;
FIG. 75 is a front view of the FIG. 73;
FIG. 76 is a rear view of the FIG. 73;
FIG. 77 is a left view of the FIG. 73;
FIG. 78 is a right view of the FIG. 73;
FIG. 79 is a top view of the FIG. 73;
FIG. 80 is a bottom view of the FIG. 73;
FIG. 81 is a front perspective view of the tenth module;
isolated for clarity of illustration;
FIG. 82 is a rear perspective of FIG. 81;
FIG. 83 is a front view of the FIG. 81;
FIG. 84 is a rear view of the FIG. 81;
FIG. 85 is a left view of the FIG. 81;
FIG. 86 is a right view of the FIG. 81;
FIG. 87 is a top view of the FIG. 81;
FIG. 88 is a bottom view of the FIG. 81;
FIG. 89 is a front perspective view of the first configuration
of a combined open sign with replaceable modules;
FIG. 90 is a front perspective view of the second configura-
tion of a combined open sign with replaceable modules;
FIG. 91 is a front perspective view of the third configura-
tion of a combined open sign with replaceable modules;
FIG. 92 is a front perspective view of the fourth configura-
tion of a combined open sign with replaceable modules;
FIG. 93 is a front perspective view of the fifth configura-
tion of a combined open sign with replaceable modules;
FIG. 94 is a front perspective view of the sixth configura-
tion of a combined open sign with replaceable modules;
FIG. 95 is a front perspective view of the seventh configura-
tion of a combined open sign with replaceable modules;
FIG. 96 is a front perspective view of the eighth configura-
tion of a combined open sign with replaceable modules;
FIG. 97 is a front perspective view of the ninth configura-
tion of a combined open sign with replaceable modules; and,
FIG. 98 is a front perspective view of the tenth configura-
tion of a combined open sign with replaceable modules.
The broken line portion of the figure drawings is included to
show environment that form no part of the claimed design.
The dot-dash broken lines define the bounds of the claimed
design and form no part thereof.
